HAND PRESS

Abraham Alk, Paterson, N. J.

Application August 26, 1946, Serial No. 693,106

10 Claims. (Cl. 100—67)

1

The invention relates to presses and more particularly to hand operated presses.

One of the principal objects of my invention is to provide a hand operated press which is simple in construction, light in weight and easy to handle.

Another object of my invention is to provide a hand operated press which translates small applied force into a powerful pressure.

Another object of my invention is the provision of a hand operated press capable of receiving and pressurizing equally well bulky material as well as material of small thickness.

A further object of my invention is to provide a hand operated press consisting of inexpensive parts which may be easily and cheaply replaced.

A still further object of my invention is to provide a hand operated press wherein the amount of pressure exerted may easily and speedily be adjusted.

Further objects and advantages of the invention will be set forth in part in the following specification and in part will be obvious therefrom without being specifically referred to, the same being realized and attained as pointed out in the claims hereof.

Desirable features for hand presses include compactness, light weight and provisions for a suitable ratio of force applied in relation to pressure obtained, and generally these features may be found in hand presses now in use. However, most manually operated presses are deficient in large leverage to facilitate the exertion of pressure and in latching means for maintaining the desired pressure after the manually applied force has ceased.

I have provided a manually operated press which overcomes these difficulties and has otherwise desirable advantages over devices heretofore known.

With the above and other objects of my invention in view, the invention consists in the novel construction, arrangement and combination of various devices, elements and parts, as set forth in the claims hereof, certain embodiments of the same being illustrated in the accompanying drawings and described in the specification.

In the accompanying drawings,

Fig. 1 is a perspective view of a press embodying my invention;

Fig. 2 is a sectional view taken along line 2—2 of Fig. 1;

Fig. 3 is a fragmentary view, in perspective, partly in section, showing details of the strap arrangement;

2

Fig. 4 is a sectional view taken along line 4—4 of Fig. 2; and

Fig. 5 is a fragmentary elevational view showing a modification.

In carrying the invention into effect in the embodiments which I have selected for illustration in the accompanying drawings and for description in this specification, and referring now particularly to Fig. 1, I provide a lower board 11 and an upper board 12 oppositely arranged thereto. Between said boards a material 13 is placed for receiving pressure from said two boards. As shown most clearly in Fig. 2, the lower board 11 has an upper surface 14 which is flat and in engagement with the material 13; similarly, the upper board 12 has a flat bottom surface 16 in engagement with the material 13.

Said lower board 11 is provided with a continuous groove generally designated 17, disposed in three exterior surfaces thereof. Said groove 17 is composed of a straight portion 18 located about midway in the lower surface 19 of said lower board 11 and of two oppositely arranged groove portions 21 and 22 arranged in the side surface 20 of said lower board connecting the upper surface 14 and the lower surface 19 thereof. The intersections of said groove portions are rounded as indicated at 23 and said groove 17 moreover has a smooth surface throughout for minimizing friction therein.

Said upper board 12 has a side surface 24 connecting the lower surface 16 and the top surface 26 thereof and, in alignment with said opposite grooves 21 and 22 of said lower board 11, said side surface 24 has opposite grooves 27 and 28, respectively. The intersections of said grooves with the upper surface 26 are also rounded, as indicated at 29, to minimize friction.

Two spaced hooks 31 are secured to the top surface 26 and disposed substantially centrally thereon; these hooks may be screwed into the board 12 or secured thereto by any other well known suitable means. A strap 32 having a width slightly smaller than the width of said grooves and having a thickness smaller than the depth of said grooves encircles completely said boards 11 and 12, as best shown in Fig. 2. A part of said strap 32 is placed in said grooves and, since these are provided with smooth surfaces and rounded intersections, the friction between said strap 32 and said grooves is negligible.

Said strap 32 has a rough surface propitious for frictional surface engagement for the purpose described later on; it may be made of woven textile or roughened leather or similar suitable

material of high friction, great tensile strength and preferably of small elasticity.

Said strap 32 has two end portions 33 and 34 near the ends of said strap. One of said end portions, designated 33, forms a loop 36 which carries a rod 37 projecting sideways thereof in two opposite directions. The projecting ends of said rod 37 are detachably engaged by said hooks 31 for removably securing said one end portion 33 of said strap 32 with relation to said upper board 12.

The strap 32 is thus fixed with one end to the upper board 12 and extends from there around said two boards 11 and 12 encircling the same exteriorly, and the other end portion 34 of said strap 32 passes through a space provided between said two hooks 31 and said first end portion 33 and the upper surface 26, and extends for a portion between said surface 26 and a part of said strap near said first end portion 33. Thereby, the two end portions 33 and 34 of said strap overlap each other and are arranged adjacent and, for a portion, in contact with each other.

A cylindrically shaped roller 36 is located beneath a part near said first end portion 33 of said strap 32 and above said top surface 26. Said second end portion 34 of said strap 32 is secured by nails 35 to said roller 36 and said roller is rotatable around its cylindrical axis in its position for winding said second end portion 34 of the strap 32 thereon and therefrom. Said roller, furthermore, is provided with two spaced rows of radially arranged bores 38, each bore of one row having a corresponding one in the other row parallel therewith.

A detachable bifurcated handle 39 is provided with two legs 40 spaced for a distance equal to the distances between said two rows of bores 38. Said handle 39 may be manually inserted into a selected pair of bores, as best shown in Fig. 1, for imparting a rotating motion to said roller 36.

In Fig. 5 I have shown a modified hook 44 which is fastened to the upper board 12 by means of a countersunk screw 46.

The operation of my device is as follows:

The material 13 is placed upon the upper surface 14 of the lower board 11 and subsequently the upper board 12 is placed thereon with its bottom surface 16 in contact with the material 13.

The roller 36 to which said free end portion 34 is fastened by means of nails 35, is placed on top of the upper board 12, as shown in Fig. 2. Thereafter the strap 32 is slung between the two hooks 31 (or 44 in Fig. 5) and placed in sequence in the grooves 27, 21, 18, 22 and 28, and placed atop the roller 36. The rod 37 is thereafter placed in the loop 36 of the strap and the projecting ends of the rod are placed in the hooks 31 (or 44, respectively).

Subsequently the roller 36 is rotated so that said free end portion 34 is wound around the surface of the roller 36. For this purpose the handle 39 is inserted with its legs 40 into a pair of bores 38 to impart manually the rotating motion to the roller 36. The rotation may be either counterclockwise following the arrow 42 or clockwise following the arrow 43 with respect to Fig. 1, so that the resultant end position will then either be in accordance with Fig. 2 or with Fig. 5, respectively, depending upon the rotation applied. In either case the strap 32 will be tensioned longitudinally until the desired pressure has been reached. By this turning of the roller 36, the strap which is engaged to the exterior of the two

boards substantially frictionless, will cause the boards to move together, thereby exerting pressure onto the material 13. The surfaces of the two end portions of the strap 32, which are in contact along a portion of the surface of the roller 36, will be frictionally interengaged, the friction increasing with increasing tension of the strap due to the downward pressure component exerted from the strap onto the roller 36 and indicated by an arrow 41 (see Fig. 2).

The handle 39 may then be removed and the pressure will continue due to the friction of the overlapping ends of the strap 32 which prevents a disengagement thereof and continues the pressure until such time as the roller 36 is rotated in an opposite direction, clockwise for the embodiment shown in Fig. 2 and indicated by the arrow 43 and counterclockwise for the modification shown in Fig. 5 and indicated by the arrow 42, by means of the handle 39 for releasing the tension and pressure of the press.

I do not limit myself to the particular details of construction set forth in the foregoing specification and illustrated in the accompanying drawings, as the same refer to and set forth only certain embodiments of the invention and it is obvious that the same may be modified, within the scope of the appended claims, without departing from the spirit and scope of the invention.

Having thus described the invention, what I claim as new and desire to be secured by Letters Patent, is as follows:

1. In a hand press manually operable to compress material between two flat surfaces, the combination with two oppositely disposed boards each having a flat surface in contact with said material and said boards movable in opposite directions to and from each other for increasing and decreasing pressure exerted against said material, of clamping means comprising strap means having a body portion encircling exteriorly said two boards and having two ends, one of said ends removably secured to the exterior of a board, and tightening means disposed between said body portion and the exterior of a board and adapted to engage the other end of said strap means and manually operable for winding said end around said tightening means, whereby said strap means will be tensioned, in proportion to the progressing winding, to exert pressure against said boards and against said tightening means for frictionally latching the same in position upon cessation of the manually applied winding force.

2. In a hand press the combination with two oppositely disposed boards adapted to move relative to each other for receiving a material therebetween in pressure engagement, of clamping means comprising a longitudinal strap adapted to encircle said two boards exteriorly and having two end portions in overlapping frictional interengagement, one of said end portions connected with relation to the exterior of one of said boards, the other end portion overlapping between said first end portion and said board, and means adapted to engage said second end portion, said means disposed between said first end portion and said board and arranged to move said second end portion with relation to said first end portion, whereby said strap will be longitudinally tensioned and the friction between said overlapping end portions increased.

3. In a hand press, the combination with two oppositely disposed boards adapted to receive material to be pressed therebetween and to exert pressure thereagainst, of clamping means com-

prising strap means having two ends and adapted to encircle said boards for causing the same to move towards each other thereby pressing the intermediate material, manually movable means arranged to engage one of said ends of said strap means and adapted to tension said strap means, holding means detachably secured with relation to one of said boards and to the other end of said strap means for providing a fixed connection between said board and said first end of said strap means, and friction means intermediate said movable means and said strap means for keeping said strap means under tension.

4. In a hand press the combination with two oppositely disposed boards adapted to move relative to each other for receiving a material therebetween in pressure engagement, of clamping means comprising a longitudinal strap having two ends and adapted to encircle said boards exteriorly, means connected to one of said ends and to the exterior of one of said boards for providing a connection therebetween, movable tightening means disposed adjacent said connecting means including a cylindrical member adapted to engage the other end of said strap means and arranged between said encircling strap means and the exterior of said one board so that it will be frictionally held in position thereby when said strap is sufficiently tensioned.

5. In a hand press the combination with two oppositely disposed boards adapted to move relative to each other for receiving a material therebetween in pressure engagement, of clamping means comprising a longitudinal strap adapted to encircle said boards and having two ends, one of said ends secured with relation to the exterior of one of said boards and spaced therefrom, the other end disposed between the exterior of said one board and a portion of said strap means adjacent said first end for frictional engagement therewith, and movable means adapted to engage said second end and manually operable to tension said strap means and arranged intermediate the exterior of said one board and a portion of said strap means near said first end, whereby said strap means when sufficiently tensioned by said movable means will hold the same frictionally in position and maintain said strap means under tension for continuously exerting pressure from the outside against said boards.

6. In a hand press the combination with two oppositely disposed boards adapted to move relative to each other for receiving a material therebetween in pressure engagement, of clamping means comprising a longitudinal strap having a body portion and two end portions, said body portion adapted to encircle said boards exteriorly, one of said end portions connected with relation to the exterior of one of said boards, the other end portion disposed between said first end portion and the exterior of said board and in frictional contact with said first end portion, and tightening means having a cylindrical surface adapted to engage said second end portion and arranged with relation between said first end portion and said exterior of said board and manually operable to wind said second portion around the cylindrical surface thereof for completely encircling the same, whereby said strap will be longitudinally tensioned for providing pressure from the outside against said boards and at the same time against said tightening means for frictionally preventing the unwinding of said second end portion, thus perpetuating the tensioning of said strap.

7. In a hand press the combination with the two oppositely disposed boards adapted to move relative to each other for receiving a material therebetween in pressure engagement, of clamping means comprising a longitudinal strap having a body portion and two end portions, said body portion adapted to encircle said boards exteriorly, one of said end portions connected with relation to the exterior of one of said boards, the other end portion disposed between said first end portion and the exterior of said board and in frictional contact with said first end portion, rotatable tightening means having a cylindrical surface adapted to engage said second end portion and arranged with relation between said first end portion and said exterior of said board and manually operable to wind said second portion around the cylindrical surface thereof for completely encircling the same, whereby said strap will be longitudinally tensioned for providing pressure from the outside against said boards and at the same time against said tightening means for frictionally preventing the unwinding of said second end portion, thus perpetuating the tensioning of said strap, and detachable means for manually rotating said tightening means in opposite directions for increasing and decreasing tension within said strap.

8. In a hand press designed manually to compress material between two flat surfaces comprising: a lower board including an upper and a lower surface, the upper surface flat and in contact with said material, the lower surface having a straight groove; an upper board oppositely arranged with relation to said lower board and including a top surface and a bottom surface, said bottom surface flat and in contact with said material; and clamping means comprising a longitudinal strap having a body portion and two end portions, said body portion adapted to encircle said boards exteriorly, a part thereof placed in said groove, said groove having a depth greater than the thickness of said strap so that no part thereof will project beyond the lower surface of said lower board, one of said end portions connected with relation to the top surface of said upper board, the other end portion disposed adjacent thereto and in contact therewith between said first end portion and the top surface of said upper board, and tightening means having a cylindrical surface adapted to engage said second end portion and arranged with relation between said first end portion and said top surface of said upper board and manually operable to wind said second portion around the cylindrical surface thereof for completely encircling the same, whereby said strap will be longitudinally tensioned for providing pressure from the outside against said boards and at the same time against said tightening means for preventing the unwinding of said second portion, thus perpetuating the tensioning of said strap.

9. In a hand press designed manually to compress material between two flat surfaces comprising: a lower board including an upper surface flat and in connection with said material, a lower surface oppositely arranged to said upper surface and a side surface between said upper and said lower surfaces and having a straight groove about midway in said lower surface and two opposite grooves in said side surface joining opposite ends of said straight groove, the joining surfaces being rounded, thereby providing a continuous exterior groove in said lower board of smooth surfaces throughout for minimizing friction therein; an

upper board oppositely arranged with relation to said lower board including a flat bottom surface in contact with said material, a top surface opposite thereto and a side surface therebetween and having two opposite grooves in said side surface in alignment with said opposite grooves of said lower board; and clamping means comprising a longitudinal strap having a body portion and two end portions, said body portion adapted to encircle said boards exteriorly, a part thereof placed in said grooves, said grooves having a depth greater than the thickness of said strap so that no part thereof will project beyond the lower surface of said lower board, one of said end portions connected with relation to the top surface of said upper board, the other end portion disposed adjacent thereto and in contact therewith between said first end portion and the top surface of said upper board, and tightening means having a cylindrical surface adapted to engage said second end portion and arranged with relation between said first end portion and said top surface of said upper board and manually operable to wind said second portion around the cylindrical surface thereof for completely encircling the same, whereby said strap will be longitudinally tensioned for providing pressure from the outside against said boards and at the same time against said tightening means for preventing the unwinding of said second portion, thus perpetuating the tensioning of said strap.

10. In a hand press the combination with two oppositely disposed boards adapted to move relative to each other for receiving a material therebetween in pressure engagement, of clamping means comprising a longitudinal strap having a body portion and two end portions, said body portion adapted to encircle said boards exteriorly, one of said end portions forming a loop, a rod

carried in said loop having opposite ends each projecting sideways beyond said strap, two spaced hooks secured to the outer surface of one of said boards and each in detachable engagement with a projecting end of said rod for removably connecting said rod to said one board and spacing it therefrom for a distance, the other end portion disposed between said first end portion and the exterior of said board and in frictional contact with said first end portion, and tightening means having a cylindrical surface adapted to engage said second end portion and arranged with relation between said first end portion and said exterior of said board and manually operable to wind said second portion around the cylindrical surface thereof for completely encircling the same, a portion of said strap near said second end portion passing between said first end portion and the exterior of the board intermediate said two spaced hooks, said end portions in frictional engagement, whereby said strap may be longitudinally tensioned for providing pressure from the outside against said boards and at the same time against said tightening means for frictionally preventing the unwinding of said second end portion, thus perpetuating the tensioning of said strap.
